(57) **CLAIM**

The ornamental design for a multitool, as shown and described.

DESCRIPTION

FIG. 1 is a perspective view of a multitool showing our new and ornamental design;

FIG. 2 is an alternate perspective view thereof;

FIG. 3 is a front elevation view thereof;

FIG. 4 is a back elevation view thereof;

FIG. 5 is side elevation view thereof;

FIG. 6 is an alternate side view thereof;

FIG. 7 is a bottom plan view thereof;

FIG. 8 is a top plan view thereof;

FIG. 9 is a perspective exploded view thereof;

FIG. 10 is an alternate perspective exploded view thereof;

FIG. 11 is a front exploded view thereof;

FIG. 12 is a back exploded view thereof;

FIG. 13 is a side exploded view thereof; and,

FIG. 14 is an alternate side exploded view thereof.

The portions of the multitool shown in broken lines in the figures attached hereto form no part of the claimed design. The exploded views and bracket to the side thereof are intended to show the relationship and order of parts in the assembly of the multitool when it is separated.
